UNITED STATES PATENT OFFICE

FRANK WAYLAND, OF SALEM, MASSACHUSETTS

LEATHER SHAVING MACHINE

Application filed August 19, 1930. Serial No. 476,326.

This invention relates to leather shaving machines of the kind employed in tanneries and other leather working establishments. Heretofore it has been considered substantially impossible to shave green hides direct out of pickle, although attempts have been made to do so by first subjecting the hide to heavy pressure to expel a part of the moisture, but the use of heavy pressure, at this stage 5 in the process, is undesirable since it compacts the hide and makes it more resistant to penetration by the tanning liquor. On the other hand it is highly desirable to shave the hide before tanning since the shavings 10 from the untanned hide have considerable commercial value, while the removal of the undesirable portions of the hide before tanning results in the saving in the tanning agent employed.

20 The present invention provides an improvement in means by which the hides, whether tanned or untanned, may be delivered to the rotary shaving cutter. General characteristics of the apparatus hereinafter set forth 25 are illustrated and described in my copending applications, Serial No. 384,635, filed August 9, 1929; Serial No. 425,810, filed February 4, 1930; and Serial No. 468,314, filed July 16, 1930, the latter disclosing one desirable 30 form of work-feeding means. The present invention pertains to an improvement in feeding means of the general type disclosed in the last-named application.

In the accompanying drawing I have illustrated in side elevation, partly in section, a leather shaving machine embodying my improved feeding means.

In the illustrated construction the bed roll support 2 is pivotally mounted at the point 3 of the main frame 1 and this bed roll support carries my improved feeding devices. This support is arranged to be oscillated toward and from the rotary cutter 14 by means similar to that disclosed in my aforesaid co-pending applications, such means comprising a treadle lever 5, connecting links 6 and 7, and a toggle device 8 adapted to move the upper end of the support toward the cutter 45 when the treadle is depressed and to lock the support in operative position.

An endless conveyor belt or apron 9, which may be of any suitable material, for example canvas, rubber, flexible metal, or the like is supported by spaced parallel rolls 10 and 11 journaled in suitable bearings carried by the 55 support 2. The roll 11 is arranged in closely spaced relation and parallel to the bed roll 12, the latter as usual having a hard (e. g. metallic) surface and cooperating with the cutter 14 during the shaving operation. The 60 rolls 11 and 12 are rotated in the same direction in any suitable manner, as for example by means of a drive belt or chain 13 passing around pulleys or sprockets on the ends of the rolls 11 and 12 and driven through any 65 suitable train of belts or gearing from the drive shaft 15 of the machine. The driving connections may be such as to rotate the rolls 11 and 12 continuously while the machine is 70 running, or preferably as is disclosed in my aforesaid applications, so as to turn these rolls only when the bed roll is substantially in operative position for cooperation with the cutter 14. Since the rolls 11 and 12 turn 75 in the same direction it will be evident that the upper work-supporting run of the belt or apron 9 will travel in the same direction as the upper surface of the bed roll 12, and thus any work resting upon the upper surface of the conveyor belt will be stripped off 80 from the latter by contact with the bed roll when it reaches the delivery end of the belt.

At the extreme front of the support 2 I prefer to arrange an idler roll 16, free to turn in suitable bearings, and constituting a rest 85 against which the operator may lean as he presents the work to the machine.

For stripping the work from the bed roll I prefer to provide a thin wedge-like blade 17 having its edge in close proximity to the 90 bed roll so as to peel the work from the roll after the cutting operation. A roll 18 may, if desired, be arranged below the bed roll 12 to assist in supporting the latter, while the pinch roll 12^a, preferably power driven, is 95 arranged above the bed roll to assist the latter in advancing the work toward the cutter.

When the support is in operative position, the apron 9 is so driven that its upper run 100

approaches the roll 12. The operator places a hide on the apron and moves it about to bring it into the best position for action by the cutter. In thus positioning the hide the 5 operator may lean against the depending portion of the hide, pressing it against the roll 16 so as to afford a firm grip for holding the work back to some extent against the pull of the apron. The hide tends to stick closely 10 to the apron but by arranging the bed roll outside of the apron and moving the roll and apron in the same direction, the bed roll strips the hide from the apron, and after shaving, the wedge member 17 easily strips the hide 15 from the bed roll. The apron is not directly opposed to the cutter, and thus may be made of any suitable material, for example canvas or rubber, since the cutter acts directly 20 against the hard metallic surface of the bed roll.

While the arrangement above described is desirable for the purpose, I contemplate that other and equivalent arrangements may be employed without departing from the spirit 25 of the invention.

I claim:

1. A leather shaving machine comprising a cutter, a bed roll having a hard work-supporting surface cooperable with the cutter, 30 and a conveyor device terminating closely adjacent to the bed roll for delivering the work to the latter.

2. A leather shaving machine comprising a cutter, an endless apron having a work- 35 supporting and advancing surface, and a hard surfaced bed roll at the end of said surface, the bed roll being so arranged and so driven relatively to the work-supporting and advancing surface of the apron as to strip 40 the work from the latter.

3. A leather shaving machine comprising a cutter, and means for presenting work to the cutter comprising closely spaced parallel rolls adjacent to the cutter, one roll being a 45 hard surfaced bed roll, the other roll forming one support for an endless work-feeding apron, and means for rotating both rolls in the same direction.

4. In a leather shaving machine including 50 a cutter, a bed roll cooperating therewith, an endless apron for feeding the work to the bed roll, and a freely rotatable roll adjacent to the receiving end of the apron.

5. In a leather shaving machine including 55 a cutter, an endless feed apron supported upon parallel rolls, a bed roll parallel to one of the apron rolls and arranged to receive the work from the apron and to cooperate with the cutter in shaving the work, means to strip 60 the work from the bed roll after it passes the cutter, and a freely rotatable roll adjacent to the receiving end of the apron and against which the operator may press the work to assist in controlling it.

6. A leather shaving machine comprising

a cutter, an endless feed apron supported upon parallel rolls, a hard surfaced bed roll closely adjacent and parallel to one of the apron-supporting rolls, and means to strip the work from the bed roll after it passes the 70 cutter.

7. A leather shaving machine comprising a cutter and means for presenting work to the cutter comprising parallel rolls adjacent to the cutter, one roll being a bed roll and the other roll constituting one support for an endless work-feeding apron, means for rotating both rolls in the same direction, and another set of parallel rolls spaced from said first set, one roll of the second set forming another support for said endless apron and the other roll being so located as to permit the operator to lean against it in guiding the work.

8. In a leather shaving machine including a cutter, means for feeding work to the cutter, comprising a movable support, a bed roll thereon, a freely rotatable roll mounted on said support parallel to said bed roll, and spaced therefrom, means for transferring work from said last-named roll to said bed roll and means for moving said support bodily toward said cutter to bring the bed roll into 85 cooperative relation therewith.

9. In a leather shaving machine including a cutter, means for feeding work to the cutter, comprising a movable support, a bed roll thereon, a freely rotatable roll mounted on said support parallel to said bed roll and spaced therefrom, intermediate rolls on said support parallel to and adjacent said bed roll and said freely rotatable roll, an apron carried by said intermediate rolls, and by which work is transferred from the freely rotatable roll to the bed roll, and means for moving said support bodily toward said cutter to 95 bring the bed roll into cooperative relation therewith.

10. In a leather shaving machine including a cutter, means for feeding work to the cutter, comprising a movable support, a bed roll thereon, a freely rotatable roll mounted on said support parallel to said bed roll and spaced therefrom, means for transferring work from said last named roll to said bed roll, a pinch roll mounted adjacent said cutter and independent of said support and means for moving said support bodily toward said cutter and pinch roll to bring said bed roll into cooperative relation therewith.

11. In a leather shaving machine including a cutter, means for feeding work to the cutter, comprising a movable support, a bed roll thereon, a freely rotatable roll mounted on said support parallel to said bed roll and spaced therefrom, intermediate rolls on said support parallel to and adjacent said bed roll and said freely rotatable roll, respectively, roll and said freely rotatable roll, respectively, an apron carried by said intermediate rolls and by which work is transferred from the 120 125 130

freely rotatable roll to the bed roll, a pinch roll mounted adjacent said cutter and independent of said support and means for moving said support bodily toward said cutter and pinch roll to bring said bed roll into cooperative relation therewith.

Signed by me at Boston, Massachusetts,
this 15th day of August, 1930.

FRANK WAYLAND.
